POWER-DRIVEN TOOL

Carl S. Schlenzig, Upper Darby, Pa.

Application October 26, 1944, Serial No. 560,397

5 Claims. (Cl. 51—166)

This invention relates to a power driven tool, more specifically adapted to use in the finishing of metal stampings and the like as by grinding, polishing and the like.

The tool in accordance with this invention, in its practical adaptation, affords duplicate facilities for a plurality of operations, as in the finishing of metal stampings, the duplicate facilities being driven from a single source of power and at the same time being independently controllable by the operators which they respectively serve.

The tool in accordance with this invention has been found admirably adapted in practice for the finishing of metal stampings, such as airplane structural elements which require as a final operation the smoothing of cut edges, the removal of burrs and polishing. As will appear many other uses for the tool will be obvious.

Broadly speaking the tool according to this invention comprises a table provided at intervals in its longitudinal extension with slots through which extend spindles for the reception at their upper ends above the surface of the table of grinding or polishing means, as, for example, a grinding wheel, a wrap of steel wool. The spindles are pivotally mounted beneath the tables and are provided with a cylindrical or pulley section adapted to be engaged with an endless belt traveling beneath the table under the drive of a single source of power, as an electric motor positioned adjacent one end of the table.

The spindles are equipped with springs tending to turn them on their pivotal mountings so that their cylindrical or pulley sections will engage the belt so that the spindles will be rotated. The degree of power applied to the spindles, however, will depend upon the pressure applied by an operator, through the work, to the grinding or polishing means carried by the spindles.

The slots in the table will be of length to permit the pulley sections of the spindles to be pressed freely against the belt by an operator, of a length to permit an operator to disengage them from the belt, usually against the springs, and of a width to permit the arcuate movement resultant from the pivotal mounting of the spindles. Preferably, though not necessarily, the slots will be arcuate and will be provided with a notch or enlarged at their outer ends for engagement of the spindles to hold them in positions disengaged from the belt.

In a preferential embodiment of this invention, rows of spindles will be provided adjacent opposite sides of the table spaced to provide access for an operator to each of them, or arranged

in spaced groups, as, for example, pairs, permitting access for an operator to each group, where the respective operators perform a plurality of operations requiring different means, as a grinding wheel and a polishing device.

Where rows of spindles are provided on opposite sides of the table, it is contemplated that the table will be longitudinally slotted between the rows of spindles and an air duct provided beneath the table into which the slot opens for the constant removal, under the influence of a suction device, as a fan, of dust created by the operations.

Having now indicated in a general way the nature and purpose of this invention, I will proceed to a detailed description of a preferred embodiment with reference to the accompanying drawing, in which:

Figure 1 is a plan view partly in section of a tool embodying this invention.

Figure 2 is a sectional view on line 2—2 of Figure 1.

Figure 3 is a partial sectional view showing a detail of construction.

In the several figures, 1 indicates a table, which may be of any length, and which is desirably provided at its longitudinal edges with depending members 2 which, as will be seen, serve as guards. The table 1 may be supported on any suitable legs or frames bearing on a floor.

The table 1 is provided intermediate its longitudinal edges with a longitudinally extending slot 3 which opens into a duct 4 connected at one end with the intake side of a blower or fan, not shown.

Adjacent its longitudinal edges the table is provided with longitudinally spaced slots 5, which, as shown, are preferably arcuate and terminate at their outer ends in enlarged portions 6.

Beneath the table 1 on opposite sides of the duct 4 are a pair of supports, each comprising, as shown, a pair of vertically spaced parallel pipes, 7, 7.

Clamped to the supports at spaced intervals and on a vertical axis are guide pulleys 8, 8. The pulleys 8, 8 are, preferably, respectively positioned adjacent to the inner ends of the slots 5, as shown in Figure 1.

About the pulleys 8, 8 extends a continuous belt 9 adapted to be driven from a single source of power, as an electric motor 17, located and supported beneath one end of the table.

Clamped to the supports, comprising pipes 7, 7 adjacent to the pulleys 8, 8 are brackets 10, 10, each of which supports a vertically extending

member 11, on the upper end of which is pivotally mounted on an arm 12. Secured to each of the arms 12 is a vertically extending spindle 13 the upper portion of which is tapered, as at a, and extends through slot 5 in the table, to a point above the surface of the table, and each is provided with a cylindrical or pulley section, as at b, in line with the belt 9.

A spring 14 surrounds each of the members 11 and attached at its ends to bracket 10 and arm 12 tends to hold the pulley portion b of the spindle 13 against the belt 9, which if the belt be driven effects drive of the spindle.

To the upper ends of the spindles 13 any desired device for grinding or polishing, or other operation, as a wrap of steel wool 15, a grinding wheel 16, may be removably applied.

As will now be apparent, if the belt 9 be driven the several spindles 13 will be driven due to the action of spring 14 in pressing the pulley sections b of the spindles against the belt.

If now an operator desires to grind a piece of work, any given spindle, which is but loosely driven since the spring 14 is of no great strength, is readily manually withdrawn from its seat 5 out of driving relation with the belt. A grinding wheel 16 is applied to the spindle and it is released into driving relation with the belt. The operator then applies the work to the rotating grinding wheel and exerts such pressure upon the work as will press the pulley section of the spindle against the belt to give a suitable grinding speed.

As will be clear, any spindle can be operated for any given operation or taken out of operation independently of any other spindle and without shutting down the source of power.

When for any reason it is desired to have a spindle out of operation for any considerable length of time, it may be drawn away from the belt into the enlarged end portion of the slot 5 where it will be held as by a detent.

During the operation of the tool described suction will be on duct 4 for the withdrawal of dust through slot 3 from the point of grinding or other operation.

It will be appreciated that various modifications of the embodiment of this invention described in detail above may be made without departing from the scope of the appended claims.

What I claim and desire to protect by Letters Patent is:

1. A power driven tool of the character described comprising a table, a plurality of slots spaced longitudinally adjacent to and extending inwardly from an edge of said table, an endless belt guided to run edgewise beneath said table, means to drive said belt, a spindle for the reception of a working element extending through each of said slots, pivotal mountings for said spindles supported beneath the table, and pulley elements carried by said spindles for engagement with said belt whereby the spindles will be driven, said spindles respectively being movable in said slots on their pivotal mountings to engage and disengage said pulley elements with respect to said belt.

2. A power driven tool of the character described comprising a table, a plurality of arcuate slots spaced longitudinally adjacent to and ex-

tending inwardly from an edge of said table, an endless belt guided to run edgewise beneath said table, means to drive said belt, a spindle for the reception of a working element extending through each of said slots, pivotal mountings for said spindles supported beneath the table, and pulley elements carried by said spindles for engagement with said belt whereby the spindles will be driven, said spindles respectively being movable in said arcuate slots on their pivotal mountings to engage and disengage said pulley elements with respect to said belt.

3. A power driven tool of the character described comprising a table, a plurality of slots spaced longitudinally adjacent to and extending inwardly from an edge of said table, said slots being enlarged at their ends adjacent the edge of said table, an endless belt guided to run edgewise beneath said table, means to drive said belt, a spindle for the reception of a working element extending through each of said slots, pivotal mountings for said spindles supported beneath the table, and pulley elements carried by said spindles for engagement with said belt whereby the spindles will be driven, said spindles respectively being movable in said slots on their pivotal mountings to engage and disengage said pulley elements with respect to said belt.

4. A power driven tool of the character described comprising a table, a plurality of slots spaced longitudinally adjacent to and extending inwardly from an edge of said table, an endless belt guided to run edgewise beneath said table, means to drive said belt, a spindle for the reception of a working element extending through each of said slots, pivotal mountings for said spindles supported beneath the table, pulley elements carried by said spindles for engagement with said belt whereby the spindles will be driven, said spindles respectively being movable in said slots on their pivotal mountings to engage and disengage said pulley elements with respect to said belt, and springs operative on said spindles whereby the pulley elements carried thereby will be normally held in a driving relation with said belt.

5. A power driven tool of the character described comprising a table, a plurality of arcuate slots spaced longitudinally adjacent to and extending inwardly from the opposite side edges of said table, a duct opening through the top of said table and extending longitudinally beneath said table intermediate its side edges, means to withdraw air from said duct, an endless belt guided to run edgewise beneath said table, means to drive said belt, a spindle for the reception of a working element extending through each of said slots, pivotal mountings for said spindles supported beneath the table, pulley elements carried by said spindles for engagement with said belt whereby the spindles will be driven, said spindles respectively being movable in said arcuate slots on their pivotal mountings to engage and disengage said pulley elements with respect to said belt, and springs operative on said spindles whereby the pulley elements carried thereby will be normally held in a driving relation with said belt.

CARL S. SCHLENZIG.
